UNITED STATES PATENT OFFICE.

JOSEPH A. GENDRON, OF NASHUA, NEW HAMPSHIRE.

SHUTTLE-MOTION FOR LOOMS.

No. 845,345.

Specification of Letters Patent.

Patented Feb. 26, 1907.

Application filed July 28, 1905. Serial No. 271,610.

To all whom it may concern:

Be it known that I, JOSEPH A. GENDRON, of Nashua, in the county of Hillsboro and State of New Hampshire, have invented certain new and useful Improvements in Shuttle-Motions for Looms, of which the following is a specification.

This invention relates to looms, and has particular reference to that type in which the shuttle is given a positive movement on the lay, being pushed partly across the lay between the warp-threads by one carrier mechanism or shuttle-carrying slide and drawn the balance of the distance by another carrier mechanism or shuttle-carrying slide, the shuttle being transferred from one carrier to the other. In such looms means are provided for alternately opening and closing the jaws or fingers which are carried by the slides.

One of the objects of my invention is to provide simple connections which will cause the shuttle-carrying slides to be reciprocated by the movement of the lay.

Another object of the invention is to provide a loom of this character in which part of the necessary reciprocating movements of the shuttle will be produced by movement of the shuttle-carriers themselves and the rest of the movements of the shuttle produced by movements of the shuttle-fingers to and from the carriers, all of these movements being positive.

Another object of the invention is to provide automatic means for causing the shuttle-grasping jaws or fingers to close on the shuttle alternately.

Other objects of the invention are to simplify various parts of a loom of this character, as will be pointed out hereinafter.

To these ends the invention consists in the construction and combination of parts, substantially as hereinafter described and claimed.

Of the accompanying drawings, Figure 1 represents a plan view of a sufficient portion of a loom to illustrate my present invention. Fig. 2 represents a front elevation thereof, partly broken away. Fig. 3 is a view similar to Fig. 1, showing some of the parts of the loom in a different position. Figs. 4 and 5 are detail elevations of the cam-operating device, enlarged, the actuating-pawl being shown in different positions. Fig. 6 is a detail end elevation, partly in section, of the parts in the position in which they are shown in

Fig. 1. Fig. 7 is a view similar to Fig. 6, but showing the parts in a different position. Fig. 8 represents an enlarged detail elevation from the inside of the lay of a carrier and its adjacent parts. Fig. 9 represents a vertical section through Fig. 8 looking to the right of said figure. Fig. 10 is a view similar to Fig. 8, showing the parts in a different position. Fig. 11 is a plan view, partly broken out, of the parts shown in Fig. 10. Fig. 12 is a detail plan view of the cam-plate which actuates the shuttle-grasping fingers.

Similar reference characters indicate the same or similar parts throughout the several views.

The frame 20, breast-beam 21, lay 22, swords 23, pivoted at 24, the crank-shaft 25, and the links 26 are represented as of ordinary construction and need not be described in detail herein. Briefly stated, the rotation of the crank-shaft 25 oscillates the lay between the position represented in Figs. 1 and 6 and the position represented in Figs. 3 and 7.

The lay 22 is formed with a way or channel 27, which is best shown in Figs. 8 and 9, the lay having, preferably, also top plates 28 to receive the wear of the shuttle-carrier 29, which reciprocates thereon. An arm 30, projecting downward from the carrier and having a lateral arm extending out from the channel or way 27, is provided with ears 31 to support a pin 32. A two-part link 33, the two parts being swiveled together, as shown in Fig. 1, is pivotally connected with the pin 32 and at the other end is pivotally connected with one end of an elbow-lever 34, pivoted at 35 to the breast-beam. The other arm of the elbow-lever is connected by a link 36 with the pivot-bracket 37, secured to the lay 22. It will be understood by comparing Figs. 1 and 3 that as the lay moves toward and from the breast-beam the links 36 cause the elbow-levers 34 to swing, so as to operate through the links 33 to slide the carriers toward and from each other on the lay. The carriers simultaneously approach the mid-length of the lay and simultaneously retreat therefrom toward the ends, these motions of the carriers being obtained solely by the movements of the lay. These movements of the carriers are positive, and the connections are such that the friction is very slight.

To grasp the shuttle alternately at its opposite ends and then release it, I provide each carrier with yielding extensions or fin-

gers 38. These extensions or fingers are preferably formed by bending a strip of resilient metal to a U shape, as indicated in Fig. 11, the bottom of the U being embraced by the forward ends of the side plates of the carrier, but sliding relatively thereto, as will be hereinafter described. They are so formed as to have a normal tendency to spring apart, as indicated at the right-hand end of the shuttle 39 in Fig. 1. Each extension 38 is formed with an inwardly-projecting lug 40, (see Figs. 10 and 11,) and these lugs project over and embrace inclined tongues 41, projecting from the front edge of a plate 42, which is mounted so as to have a slight reciprocal movement relatively to the shuttle-fingers 38 and their lugs 40. Said plate 42 is formed with a lug 43, to which is pivoted one end of a link 44, the other end being pivotally connected with an arm 45, said arm 45 having a pin 46, which projects out through a slot 47, (see Figs. 2 and 11,) formed in one side of the carrier. The members 44 and 45 practically constitute a jointed link for actuating the plate 42, as hereinafter described. The shape of the plate 42 and its inclined tongues 41 is best indicated in Fig. 12. It will be readily understood that by reciprocating the jointed link 44 45, so as to slide the plate 42 back and forth, the inclined sides of the tongues 41 will cause the fingers 38 to approach each other and grasp the shuttle 39 when said plate is moved forward, and when said plate is retracted the tendency of the tongues 38 to spring apart, as has been described, will cause said fingers to open and release the shuttle.

I shall now proceed to describe the mechanism for giving the two plates 42 their necessary slight reciprocal movements above referred to. A reciprocating bar 48, having slots 49, mounted on guide-pins 50, projecting from the side of the lay 22, is formed with a central depending arm 51, having a pin or roll 52, (see dotted lines in Fig. 2,) said pin or roll being acted upon by a cam 68, which will be hereinafter described. The two ends of the bar 48 are alike, and I shall describe the structure at one end. A tappet-arm 53 projects upward, and a lower arm 54 projects a short distance horizontally and carries a pin 55, engaging a slot 56 in a lever 57, which is pivoted at 58 to the lay. A yielding extension 59 of the lever 57 is pivoted to said lever 57 at 60 and is formed with an ear 61, the under side of which is engaged by the free end of a leaf-spring 62, which is secured to an ear 63 of the lever 57. This structure enables the extension 59 to yield in one direction, but not in the other, because its ear 61 extends over the edge of the lever 57. (See Figs. 1 and 2.) As shown at the left of Fig. 2, the upper end of the extension 59 is shown

as slightly below the pin 46. This is because 65 when the parts are in the position shown in said figure the said lever and its extension are supposed to have just moved from their other limit of movement and in doing so to have engaged the pin 46 and moved it from 70 the left-hand end of its slot 47 to the position in which it is shown in said figure. During such movement of the pin 46 the plate 42 at that end of the lay has been advanced and caused to draw the fingers 38 at that end in 75 contact with the shuttle. At the same time the lever 57 at the other end of the lay (at the right in Fig. 2) has moved freely away from the pin 46 at that end, and said pin 46 has been struck by the tappet-arm 53 and 80 thrown backward, so that the fingers 38 of the carrier have released the shuttle. Therefore when the parts are in the position shown in Fig. 2 they are ready to take the shuttle 39 toward the left as the lay moves from the 85 position shown in Fig. 1 to that shown in Fig. 3.

As shown most clearly in Figs. 10 and 11, a pin 64 extends through the sides of each carrier near its front end and has collars 65 secured thereto outside of the sides of the carrier. This pin and its collars prevent the spread of the sides of the carrier, and it also has another use that will be hereinafter referred to. Said pin extends through longitudinal slots 66 in the sides of the carrier. Short pins 67 project from the U-shaped strip which forms the fingers 38 near the base of the U through the same slots 66. These pins 67 are simply guide-pins to prevent the fingers 38 from oscillating during their reciprocating movements relatively to the carrier. In other words, the pins 67 and the pin 64 slide along the slots 66 and guide the fingers 38 in their horizontal plane. 105

The cam 68, which engages the pin or roll 52 and reciprocates the bar 48, is mounted with its shaft extending through a bearing 69, carried by a bracket 70, secured to one side of a strut 71, (see Figs. 2, 6, and 7,) said strut being mounted between the swords 23 and, like them, pivoted to swing on the pivot or fulcrum rod 24. The other end of the cam-shaft has secured thereto a compound ratchet having face-teeth 72 and peripheral teeth 73. A detent-ratchet 74 is also secured to said shaft, said ratchet being adapted to be engaged by a pawl 75, (see Figs. 4 and 5,) pivoted to the strut 71. Said pawl is designed simply to prevent retrograde movement of the cam. As I shall presently describe, this cam during those portions of its movement which actuate the bar 48 is given a quick or snapping movement, so that it will actuate the levers 57 smartly. The 115 cam-shaft is given a step-by-step movement by means of an actuating-pawl 76, pivotally connected with the upper end of a plunger

77, a suitable spring 78 being employed to cause the pawl 76 to engage the face-teeth 72 of the compound ratchet, as represented in Fig. 7. The means for actuating the plunger 77 I shall presently describe. In order to prevent the upward movement of the pawl 76 from actuating the cam-shaft too far, the upper end of the plunger is provided with a laterally-extending pin 79 which as the pawl reaches its upward extreme of movement stands in the path of one of the peripheral teeth 73 of the compound ratchet, so as to act as an abutment that will be engaged by such tooth to prevent excessive actuation of the cam-shaft.

The plunger 77 is mounted to reciprocate in bearings formed in brackets 80, which project from the strut 71, the lower bracket being formed with a vertical slot 81, into which a pin 82 projects from the plunger 77 to limit the vertical movements of the plunger by the length of said slot. (See Figs. 2, 6, and 7.) Secured to the frame 20 are brackets 83, having secured to their outer ends strips comprising an inclined portion 84 and an upright portion 85. The inclined portion forms a cam and the upright portion a stop, as will be presently described. Passing through the lower end of the plunger 77 is a pin 86, having freely mounted thereon trip-plates 87, which are adapted to engage the under side of the lower stationary bracket 80. These trip-plates 87 are so located as to oscillate between the brackets 83 and the cam and stop strips. As shown, the said trip-plates are pivotally mounted at one end on the pin 86, and at the outer end of each trip-plate is a pin or roller 88, which projects into the space between the cam 84 and the stop 85.

A spring 89, coiled about the plunger 77 and bearing at its lower end on the upper surface of the lower bracket 80 and at its upper end against a stop-collar 90, secured on the plunger 77, has a normal tendency to throw the plunger and its pawl 76 from the position shown in Fig. 7 to the position shown in Fig. 6. With the parts in the position shown in Fig. 7 the pin 86 and the point where the free ends of the trip-plates bear against the under surface of the lower bracket 80 are in alignment, so that said trip-plates serve to hold the plunger in its lower position; but when the lay moves toward the position shown in Fig. 6 the rollers 88 engage the inner surface of the stops 85 and are held thereby, while a slight further movement of the lay in the same direction carries the pin 86 far enough to the left so that the tension of the spring 89 will throw the plunger sharply upward, snapping the trip-plates 87 to the position substantially as shown in Fig. 6. This movement gives the cam 68 a sudden quarter-movement, enough to shift the bar 48 sharply in the manner and for the purpose

hereinbefore described. Upon the return movement of the lay the two rollers 88 engage the inclines 84 and are held thereby, so that continued movement of the lay in the same direction carries the pin 86 downward, the upper surfaces of the trip-plates 87 riding under the lower bracket 80 and the rollers 88 riding down the inclines 84, thus lowering the plunger and compressing the spring 89 and bringing the parts again to the position represented in Fig. 7 ready for a repetition of the operation just described.

I shall now describe the means which provide for withdrawing the shuttle 39 into either of the carriers 29. (See particularly Figs. 8, 9, 10, and 11.) As has been described, the pin 64 rides along the slots 66 in the carrier, and said pin passes through the sides of the shuttle-grasping yoke. Pivotally connected with this same pin 64 is a link 91, having its other end pivotally connected with an arm 92 of a rock-shaft 93, mounted in a bearing 94, formed in the side of the carrier. The outer end of the rock-shaft 93 has secured thereto an arm 95, having a pin or roll 96 at its end, said pin or roll entering a slot 97, formed in a bracket 98, which is secured to the lay. The arm 92 is provided with a lateral lug or projection 99, which underlies a similar lug or projection 100, carried by the arm 45.

The slotted bracket 98 forms a guide which is followed by the roll 96 of the rock-shaft arm 95. When the swinging movement of the lay causes the carriers to separate or move away from each other, the operation of the device just described at each end of the lay is as follows: As the carrier moves from the position shown in Fig. 10 toward the position shown in Fig. 8 the roll 96, following the guide-slot 97, turns the arm 92 upward, and said arm through the link 91, which is connected to the pin 64, draws the shuttle-grasping yoke or jaws into the carrier, thereby increasing the movement of the shuttle to a greater extent than would be imparted by the levers 34 and links 33 and 36 alone. The first upward movement of the arm 92 causes its lug 99 to engage the lug 100 of the arm 45, so that said arm 45 and the link 44 double up simultaneously with the movements of the arm 92 and link 91. Otherwise the arm 45 and link 44 would oppose the movement of the shuttle-fingers into the carrier. It is to be borne in mind that the pin 64, riding along the slots 66, aids in the movements just described. On the advance movement of the carrier the roller 96, riding up the curved portion of the slot 97, causes the arm 92 to be thrown downward or toward the left from Fig. 8, pushing on the link 91 and the pin 64, and thereby projecting the shuttle fingers or jaws from the carrier. The plate 42 is moved forward

at the same time by the operation of the bar 48 and its adjuncts, as above described, and the link 44 and the arm 45 are at the same time drawn down to a horizontal plane, as 5 represented in Fig. 10, owing to the connection of the link 44 with said plate.

- It is to be understood, of course, that the timing of the movements of the several parts is such that the operations of the different connections will be in their proper order or relation to accomplish the function of carrying the shuttle outward from one carrier toward the opposite carrier, releasing it from one finger-carrying slide as the fingers of the other slide grasp it and the shuttle being then drawn to the other end of the lay by the last-mentioned slide, the return of the shuttle being effected in the same manner.
- 20 To prevent the shuttle from oscillating in a vertical plane when grasped and being moved by the fingers 38, the latter may be provided with lugs or flanges 101 to engage the upper and lower walls of the shuttle, and thereby steady it during its rapid movements on the lay.

In the operation of the loom the movements of the lay toward and from the breast-beam in the usual manner act, through the levers 34 and the links 33 and 36, to shift the shuttle-carriers toward and from the middle gth of the lay. The fingers or extensions 38 of the shuttle-carriers are alternately contracted by the operation of the plates 42 in the manner hereinbefore described, so that the shuttle is passed from one carrier to the other. After either pair of fingers or extensions 38 has grasped the shuttle and the carrier is moved backward the shuttle-grasping 40 yoke, which comprises the fingers 38, is withdrawn into the carrier, so as to give the shuttle a greater total length of movement than would be imparted by the levers 34 and links 33 and 36 alone, unless said levers and links were made of a great length. By employing the mechanism which withdraws the shuttle-grasping fingers into the shuttle-carrier I am enabled to employ shorter levers 34 and link connections with the lay than 50 would otherwise be required.

Having now described my invention, what I claim is—

1. A positive-shuttle-motion loom having carriers mounted upon the lay, connections between the lay and a stationary part of the loom whereby the carriers are reciprocated by the movements of the lay, and means for withdrawing a shuttle alternately into the said carriers and projecting it therefrom.
2. A positive-shuttle-motion loom having carriers mounted upon the lay, connections between the lay and a stationary part of the loom whereby the carriers are reciprocated by the movements of the lay, said carriers 65 having automatically-operating jaws or fin-

gers to alternately grasp and release the shuttle, and means for actuating said fingers to cause them to alternately withdraw a shuttle into the carriers and project it therefrom.

3. In a loom of the character described, the combination with a carrier movable on the lay, of yielding extensions movable relatively to the carrier and having their outer ends normally tending to open, and means 75 for automatically and positively closing said yielding extensions.

4. In a loom of the character described, the combination with the lay and a carrier movable longitudinally thereof, of a U- 80 shaped member slidably mounted in the carrier and having its free ends adapted to grasp a shuttle, the sides of said U-shaped member being formed with inwardly-projecting lugs, a plate having beveled tongues engaging said 85 lugs, and means for reciprocating said plate relatively to the carrier.

5. In a loom of the character described, the combination with the lay and a carrier movable longitudinally thereof, of a U- 90 shaped member slidably mounted in the carrier and having its free ends adapted to grasp a shuttle, the sides of said U-shaped member being formed with inwardly-projecting lugs, a plate having beveled tongues engaging said 95 lugs, means for reciprocating said plate relatively to the carrier, and means for withdrawing the said U-shaped member and a shuttle grasped thereby into the carrier.

6. In a loom of the character described, 100 the combination with a carrier movable on the lay, and having a slot, a U-shaped member having extensions adapted to grasp the shuttle, a plate movable relatively to said U- shaped member and having connections with 105 the sides thereof to contract the latter, a jointed link connected with said plate and having a pin projecting through the slot of the carrier, and means for actuating said projecting pin lengthwise of the carrier.

7. In a loom of the character described, 110 the combination with a bar mounted on said lay, shuttle-grasping fingers actuated by said bar, a cam for reciprocating the bar, and a pawl and means for actuating said pawl to 115 impart a quick movement to said cam.

8. In a loom of the character described, 120 the combination with a bar mounted to slide on the lay, levers connected with said bar to be oscillated thereby, means for reciprocating the bar, and shuttle-controlling fingers having connections including pins located in the path of movement of the said levers.

9. In a loom of the character described, 125 the combination with a bar mounted to slide on the lay, levers connected with said bar to be oscillated thereby, means for reciprocating the bar, and shuttle-controlling fingers having connections including pins located in the path of movement of the said levers, the said 130

levers being jointed and having their outer parts yielding substantially as and for the purpose set forth.

10. In a loom of the character described, 5 the combination with the lay and shuttle-grasping fingers thereon, of a bar mounted on the lay and having connections for controlling the shuttle-grasping fingers, a cam for reciprocating said bar, a ratchet connected to the 10 shaft of said cam, a pawl for actuating the ratchet, and means for suddenly actuating the pawl.

11. In a loom of the character described, 15 the combination with the lay and shuttle-grasping fingers thereon, of a bar mounted on the lay and having connections for controlling the shuttle-grasping fingers, a cam for reciprocating said bar, a compound ratchet carried by the shaft of said cam, a pawl for engaging one set of teeth of the ratchet, said 20 pawl having a stop adapted to be interposed in the path of movement of the other set of teeth of the ratchet, and means for reciprocating said pawl.

25 12. In a loom of the character described, the combination with the lay, of a shaft mounted thereon, said shaft having a cam at one end and a ratchet at the other end, shuttle-grasping fingers on the lay, means controlled by said cam for actuating the shuttle- 30 grasping fingers, a plunger mounted in bear-

ings connected with the lay and having a pawl to engage said ratchet, trip-plates connected with the plunger and adapted to actuate the same in one direction, a spring for 35 actuating the plunger in the other direction, and means for oscillating the trip-plates according to movements of the lay.

13. In a loom of the character described, 40 the combination with the lay, of carriers movable longitudinally thereof, shuttle-grasping fingers mounted in said carriers, jointed links for retracting and projecting said fingers relatively to the carriers and means for actuating said arms. 45

14. In a loom of the character described, the combination with brackets secured to the lay said brackets having curved slots, of carriers movable on the lay, each carrier having a rock-shaft provided with an arm engaging a 50 curved slot, said rock-shaft having also a jointed link, and shuttle-grasping fingers connected with said jointed link, whereby movements of the carrier on the lay will automatically move the shuttle-fingers relatively to 55 the carriers.

In testimony whereof I have affixed my signature in presence of two witnesses.

JOSEPH A. GENDRON.
